SWITCH PLUG

John W. Hudson, St. Albans, N. Y., assignor to
Henry Hyman, Brooklyn, N. Y.

Application May 6, 1929. Serial No. 360,672

15 Claims. (Cl. 200—51)

This invention relates to an electric plug that is provided with a switch mechanism in the plug with means extending through the side of the plug for operating the switch mechanism. Heretofore, in devices of this character the switch operating means has been limited in its travel by contact with the edges of the wall of the opening in the insulating material through which it extends with the result that, when the 10 plug is made of breakable insulating material, it is likely to become chipped or cracked by the switch operating member.

By the present invention a metal stop is provided in the plug, which is so shaped and located that the switch operating member is stopped at opposite ends of its travel by coming into contact with stationary metal parts.

The invention will be understood from the description in connection with the accompanying 20 drawing in which Fig. 1 is a vertical section through an illustrative embodiment of the invention; Fig. 2 is a similar section on an enlarged scale, partly broken away, showing the switch in its closed position; Fig. 3 is a view 25 similar to Fig. 2, showing the switch in its open position; Fig. 4 is a section along the line 4—4 of Fig. 2; and Fig. 5 is a perspective view, showing some of the parts in disassembled relation.

In the drawing reference characters 1 and 2 30 indicate the two halves or side members of the switch plug, which side members are made of insulating material with recesses or spaces for housing the parts when the two side members are connected. Each side member 1 and 2 is provided with central longitudinally disposed partitions or ribs 3 to separate the inside space into two approximately equal spaces. The upper ends of the side members are provided with semi-circular grooves 4 into which the end of the spring 35 40 guard 5 for the electric wire is retained. The spring guard extends through the semi-circular holes 6 in the members 1 and 2 which make a circular hole when the members are assembled.

An elongated opening 8 is provided on one side 45 of the plug through which a switch operating member extends, and a plurality of transverse openings 9 is provided in each member 1 and 2 through which bolts extend for holding the members together.

50 A metallic insert 10, provided with an internally threaded hole, is anchored in an extension on the side member 2, preferably by molding the insulating material around it so that it will not turn. A pivot 11 has a reduced threaded 55 end extending into the threaded hole in the insert 10 and has an enlarged polygonal head 12 at the other end.

The switch operating member that extends 60 through the opening 8 is provided at its outer end with an insulating knob or button 14. The

thin shank 15 of the switch operating member extends through the elongated opening 8 and is connected to a box-like portion 16 that is open along one side. The shank 15 and the box 16 are preferably made integral with each other. 65 The box-like portion 16 is provided with holes 17 through the top and bottom sides to accommodate the pivot 11. A lip or extension 18, having its end reduced to provide a coil spring seat, is made on the side opposite the shank 15 by bending out the metal approximately at right angles to the wall, as indicated at 19.

70 A metal stop 20 in the form of a flat strip of metal is provided at one end with a hole 21 through which the pivot 11 extends and at the other end with a binding screw 22 that extends a sufficient distance through the member 20 to project into a hole that is provided in the side member 1, thus preventing the stop 20 from turning about the pivot 11. The stop 20 is provided with a stop shoulder 23 along one edge, its 75 opposite edge being straight.

A sleeve 24 (Fig. 4) is provided around the pivot 11 between the upper side of the box-like portion 16 of the switch operating member and 80 the side of the end of the strip 20 in which the hole 21 is provided to keep the strip 20 in place.

85 A switch member having flat parallel sides 25 is provided with holes 26 by which it is pivoted upon the pivot 11 with the sides 25 lying on opposite sides of the box-like portion 16 of the switch operating member. The switch member is provided with an outwardly bent end portion 27 integral with the portion 28 that connects the sides 25 and is preferably integral therewith. The portion 28 is provided along its edge opposite the end 27 with a spring seat 29 for the coil spring 30 that is interposed between the portion 28 and the lip or extension 18 of the switch operating member.

100 A groove 31 for an electric wire is provided through the partitions 3, one wall or side 32 of this groove being located in such a position that the portion 28 of the switch will come into contact therewith and be stopped thereby when the switch is in its open position.

105 Terminal clips 33 and 34 are located in the plug between the side members 1 and 2. These terminal clips may be of a well known type and the clip 33 is provided with a screw 35 that extends into a threaded metallic insert that is embedded in the side member 1, similar to the insert 10, whereby the clip 33 is securely held in position, even when struck by the switch 25. The other clip 34 is provided with a binding screw 36 110 for the other side of the circuit.

115 The operation is as follows:

120 When the knob or button 14 of the switch operating member is in the position indicated in Figs. 1 and 2, the switch is closed, the current

passing from the wire that is connected to the binding post 22 through the strip 20, pivot 11, switch 25, bent end 27 and clip 33 into the iron or other electrical device, thence back through 5 the clip 34 and binding post 36 to the other wire of the circuit.

When the switch operating member is moved into the position shown in Fig. 3, the circuit is broken. The spring seat 18 in moving from the 10 position shown in Fig. 2 to that shown in Fig. 3 compresses the spring 30 and when the spring seat 18 passes beyond the center line from the spring seat 29 to the pivot 11, the spring causes the switch 25 to be snapped into the position 15 shown in Fig. 3, the switch being stopped by the wall 32. A similar action takes place when the switch operating member is moved in the opposite direction, namely, the spring 30 causes the switch 25 to be snapped into position where 20 the end 27 contacts with the clip 33, as indicated in Fig. 2.

When the button 14 is turned into the position shown in Fig. 3, the edge of the shank 15 comes into contact with the shoulder 23 on the strip 20, 25 before the shank 15 reaches the end of the opening 8, and, therefore, does not strike the brittle insulating material. When the button 14 is turned to the position shown in Fig. 2, the bent portion 19 of the box-like portion 16 of the switch 30 operating member strikes the straight edge of the strip or stop 20, as indicated in Fig. 2, thus stopping the switch operating member before the edge of the shank 15 strikes the lower end 35 of the opening 8, thereby preventing injury to the insulating material.

I claim:

1. In a switch plug of insulating material, a pivoted contact member, a member for operating said contact member, and a metal stop inside of 40 said plug for said contact operating member at each end of its travel, said stop comprising a portion of the electric circuit through said plug.

2. In a switch plug of insulating material, a pivoted contact member, a member for operating 45 said contact member, and a metal stop anchored in said plug for said contact operating member at each end of its travel, said stop comprising a portion of the electric circuit through said plug.

3. In a switch plug of insulating material, a 50 pivoted contact member, a metallic member for operating said contact member, a metal stop anchored in said plug for said contact operating member at each end of its travel, and a binding post carried by said stop.

55 4. In a switch plug of insulating material, a pivoted contact member, a member for operating said contact member, a spring connecting said contact member and said operating member, and a metal stop inside of said plug for said contact operating member at each end of its travel, said stop comprising a portion of the electric circuit through said plug.

5. In a switch plug of insulating material, a pivoted contact member, a metallic member for 55 operating said contact member, and a metal stop anchored in said plug and attached to and supported by said insulating material, having a shoulder against which said operating member strikes, for said contact operating member at each end of its travel.

6. In a switch plug of insulating material, a switch operating member extending through the side of said plug, and a single metallic member in said plug to limit the extent of movement of 60 said switch operating member said stop comprising

ing a portion of the electric circuit through said plug.

7. In a switch plug of insulating material, a switch operating member extending through the side of said plug, a snap switch connected to said switch operating member, and a metallic member in said plug to limit the extent of movement of said switch operating member said stop comprising a portion of the electric circuit through 80 said plug.

8. In a switch plug of insulating material, a switch operating member extending through an opening in the side of said plug, and a single metallic member in said plug to limit the extent of movement of said switch operating member to prevent it from striking the sides of said opening 85 comprising a portion of the electric circuit through said plug.

9. In a switch plug, a snap switch, an operating member for said switch, a stop member for said operating member, said stop member being in the electrical circuit through the switch, and a binding post connected to said stop member.

10. In a switch plug of insulating material, a pivoted switch member, a pivoted operating member for said switch member, a compression spring between said members to provide snap action of said switch member in both directions of its movement, and a stationary metallic member anchored in said plug having stops thereon for the 105 extremities of movement of said operating member said stop comprising a portion of the electric circuit through said plug.

11. In a switch plug of insulating material, a pivoted switch member, a pivoted operating 110 member for said switch member, a compression spring between said members to provide snap action of said switch member in both directions of its movement, a stationary metallic member anchored in said plug having stops thereon for the 115 extremities of movement of said operating member, and a pivot extending through said switch member, operating member and stationary metallic member and anchored in said insulating material.

12. In a switch plug of insulating material, a pivot, a switch member pivoted on said pivot, an operating member for said switch member pivoted on said pivot, and a metallic member fixed in said plug, said pivot passing through said fixed member and said fixed member limiting the movement of said switch operating member in opposite directions.

13. In a switch plug of insulating material, a pivot, a switch member pivoted on said pivot, 130 an operating member for said switch member pivoted on said pivot and a metallic member fixed in said plug, said pivot passing through said fixed member and said switch operating member having portions on opposite sides of said pivot contacting with said fixed member at the extremities of movement of said switch operating member.

14. In a switch plug of insulating material, a pivot, and a switch operating member having a box-like portion pivoted on said pivot, said member having a handle and a projection on the other side of said box-like portion opposite said handle in a space between the planes of the side walls of said box-like portion.

15. In a switch plug of insulating material, a 145 pivot, a switch operating member having a box-like portion pivoted on said pivot, and an extension on said box-like portion on a side thereof away from the shank of said switch operating member.
